AERONAUTICAL PROPELLER

Paul J. Gathmann, Lombard, Ill.

Application June 14, 1938, Serial No. 213,646

7 Claims. (Cl. 170—162)

This invention relates to certain improvements in aeronautical propellers. One object of the invention is the provision of relatively simple and automatically operative means for changing the angular pitch of the propeller blades in response to changes of engine speed. Another object is to arrange such automatic mechanism for actuation by centrifugal force during rotation of the propeller. Further objects and the specific nature of the invention will be readily recognized by those skilled in the art, from the following description and explanation, and from the accompanying drawings illustrating certain preferred embodiments thereof; but it should be understood that various modifications and re-arrangements of the features and elements may be made without departing from the spirit and scope of the invention, and that I do not limit myself to the particular forms and combinations herein shown, except as indicated by the accompanying claims.

In the drawings:

Figure 1 is a front elevation of an aeronautical propeller with the hub cover plate removed, and with parts shown in section to reveal certain details of construction.

Figure 2 is a transverse section of the propeller taken substantially at the plane of the axis of the drive shaft and through the intersecting axis of one propeller blade.

Figure 3 is a section taken transversely through a propeller blade, and indicating its range of adjustment with respect to the plane of rotation for relatively low engine speeds.

Figure 4 is a similar section through a propeller blade indicating the range of angular adjustment employed at normal engine speeds in flying.

Figure 5 is also a section through a propeller blade showing its adjustment transversely of the plane of rotation to serve as a paddle wheel resistance or brake to prevent racing of the engine.

Figure 6 is a transverse detail section taken as indicated at line 6—6 on Figure 2.

Figure 7 is a transverse section taken as indicated at line 7—7 on Figure 2.

Figure 8 is a detail section showing the centrifugally operated weights and their inter-connection through a crank plate.

Figure 9 is an edge view of the crank plate.

Figure 10 is a detail section on a larger scale showing one of the weights and being taken substantially as indicated at line 10—10 on Figure 8.

Figure 11 is a detail section on an enlarged scale showing one of the synchronizing pinions and its control spring.

Figure 12 is a detail section taken transversely of the drive shaft and looking into the front cover plate.

Figure 13 is a front elevation of the central portion of the propeller showing the cover plate in position.

Figure 14 is a transaxial view of the hub portion of a propeller embodying the modification of the invention.

Figure 15 is a section taken as indicated at line 15—15 on Figure 14.

Figure 16 is a detail perspective view of one of the weights of Figure 14.

Referring first to Figures 1 and 2, it will be seen that the structure therein illustrated includes a chambered hub housing 10, supporting a plurality of radially disposed propeller blades, preferably of metallic material, and each mounted for easy rotative adjustment about its own axis in bearings formed in the radial branches of the housing 10, with shoulders 12 and 13 arranged to receive the radial thrust of the blades due to centrifugal force. The hub housing 10 is fixedly keyed to the propeller drive shaft 14, as by splines 14^a and 14^b, and is held in place on the shaft by a retaining nut 15 screwed onto the outer end of the shaft, as seen in Figure 2.

Each of the propeller blades 11 terminates at its root end in a hollow shank 11^a having on its inner surface a plurality of helical grooves 16. As illustrated, the propeller is provided with three blades, and the hollow shanks of these blades contain automatic controlling weights 18, 19 and 20 respectively, each formed with helical ribs or splines of suitable pitch and dimensions to inter-member with the helical grooves in the hollow propeller shanks. Thus, in response to centrifugal force generated by rotation of the propeller about the axis of its drive shaft 14, the weights 18, 19 and 20 tend to move radially outward in the shanks of the respective propeller blades, and if the weights be restrained against rotation, their movement will tend to produce rotative adjustment of the propeller blades by virtue of the inter-engagement of the helical grooves and splines.

As seen in Figure 8, the weights 18, 19 and 20 constitute a unitary assembly by virtue of their connection to a crank plate 21 which is mounted for free oscillatory movement upon the propeller shaft 14 and is formed with recesses 22, 23 and 24 in its periphery. These recesses respectively accommodate the connecting torque rods 25, 26 and 27, each having one end attached to the crank plate 21 by means of a pivot pin 21^a. At their opposite ends the rods are connected to

the respective weights by pivots 18^a, 19^a and 20^a which extend through recesses 18^b, 19^b and 20^b, in which the ends of the rods are accommodated in the respective weights. Thus the movement of any one of the weights radially outward in its propeller shank can only be accompanied by a similar and equal movement of the other weights, and any tendency to inequality in such movements as might result from differences of friction or otherwise, will be integrated and equalized by this inter-connection of the weights to the crank plate 21. At the same time, the connecting rods 25, 26 and 27, being of rectangular cross-section and fitting snugly between the parallel cheeks of the recesses 22, 23 and 24, and the cheeks of the recesses 18^b, 19^b and 20^b, operate as torque members to prevent twisting or rotative movement of the weights, thus insuring that their radial travel will cause rotative adjustment of the propeller blades.

Each of the propeller blade shanks 11^a is provided at its root end with a mitre gear 28 extending well into the hub housing 10, and these gears, in turn, mesh with synchronizing pinions 29 journaled in the wall of the housing, as seen in Figure 1.

The front side of the hub housing 10 is provided with a removable cover plate 31 within which there is enclosed a worm 32 and a worm wheel 33 meshing therewith, as best seen in Figures 2 and 12. The worm wheel 33 has a central hub sleeve 34 suitably bored to fit loosely upon the propeller shaft 14, to permit of easy rotative adjustment by operation of the worm 32. Such adjustment may be effected by means of a suitable tool, such as a socket wrench, engaging the squared end 32^a of the shaft of the worm 32, which is accessible through an opening 31^a in the cover plate 31, as seen in Figure 13.

To provide a balancing effect and prevent back-lash or vibration during rotative adjustment of the blades for changing their pitch, I arrange a yielding retracting spring 35 with its convolutions surrounding the hub sleeve 34 of the worm wheel 33. One end of the spring is secured to the crank plate 21, as indicated at 21^x, while the other end is anchored to the worm wheel 33 at 33^x. The initial tension of the spring 35 is thus adjustable by means of the worm 32. The transverse surface 33^a of a recess 33^b in the cover plate 31 serves as a thrust bearing to accurately position the worm wheel 33 in alignment with its worm 32, while the hub sleeve 34 extends into abutment with one hub of the crank plate 21, the other hub of the crank plate being fitted against the inner end surface 21^d of the rear hub bearing so that the crank plate 21 is maintained in proper relation to the common plane of the propeller blade axes.

Referring again to the synchronizing pinions 29, it may be noted that they are mounted for easy turning in the bearing blocks 40, which are suitably threaded to be screwed into position in threaded openings of the hub housing 10. Each of the pinions 29 has a stub shaft 41 protruding through the bearing block and terminating outwardly in a short, square shank 42, upon which there is mounted a collar 43, having a square hole 43^a by which it engages the shank 42 for turning therewith. A retaining nut 45 holds the collar in place. A retracting spring 46 is shown coiled around a protruding portion of the bearing block 40 and the outer end of the stub-shaft, with one end of the spring anchored to the bearing block and the other end secured to the col-

lar 43 on the stub shaft. Thus any rotative adjustment of the propeller blades, causing corresponding rotation of the pinions 29, inter-meshing with the mitre gears 28, takes place in the presence of some tension in the springs 46, which serve to take up any possible back-lash in the connections, insuring smooth, even movement throughout the range of adjustment, and avoiding vibration of the parts with respect to each other. Maintaining this spring tension and operating in opposition to it at all times is the centrifugal force created in the weights 18, 19 and 20 by the rotation of the propeller assembly. The retractor spring 35 operates in the same direction as the springs 46, so that all the springs work together to prevent looseness or vibration in the operation of the automatic adjusting features. And in order to effect a still more perfect synchronization of the parts I may provide a ring gear 50, which is formed as a mitre gear and is shown in Figure 2 as rotatively mounted on the internal hub portion 10^x of the rear bearing of the hub housing so as to mesh with the three mitre gears 28, but not with pinions 29.

It should be understood that in the drawings the parts of the invention are shown in the positions which they occupy when the propeller is not in operation, the weights 18, 19 and 20 being shown at their innermost limiting positions nearest the axis of the shaft 14, from which positions they will gradually move outwardly under the influence of the centrifugal force generated by rotation of the propeller. With the parts in the positions indicated, the retracting springs 35 and 46 are at minimum tension, but as the propeller revolves, the weights, being held against rotation by virtue of their engagement with the torque rods 25, 26 and 27 and the crank plate 21, will travel radially outward, causing the hollow shanks 11 of the propeller blades, to turn in their bearings and in opposition to the tension of the springs 46, acting through the mitre pinions 29, and to the tension of the spring 35 tending to resist rotation of the crank plate 21. Thus the centrifugal force is balanced against these variable spring tensions to insure smooth action and a definite position of each part throughout the range of adjustment. The parts are all substantially symmetrical in their arrangement about the axis of revolution, so that the perfect balance of the propeller is maintained for all speeds.

Figures 14 and 15 illustrate a modification of the structure, and although, in these views, the propeller is shown as having only two blades, it should be understood that this form of the invention is equally applicable to a propeller of three blades, such, for example, as that shown in Figures 1 to 13. In this form the hub housing A is secured by means of splines B to the drive shaft C for rotating the propeller as an entirety. Securely fastened to the shaft C within the hub housing A is a block-like sleeve D; if desired, the splines B may extend into the block D to secure it firmly to the shaft C for rotation therewith. The block D carries radially extending torque rods E, E, each of which is of square cross-section, and which may be made integral with the block D.

The hub housing A includes suitable bearings A², in which the hollow shanks of the propeller blades A¹ are mounted for easy rotative adjustment. The inner wall of the hollow shank of each propeller blade is formed with a plurality of helical grooves F which register with and engage

the helical splines G extending from the pitch-change governor weights H. These weights are preferably cup-shaped, as indicated in dotted outline on Figure 14, and as more clearly seen in Figure 15, each having a centrally upstanding hub portion J formed with a square bore K by which the weight is slidably guided on the square torque rod E for radial movement thereon. At the outer extremity of each torque rod there is secured a shouldered nut L, the extreme end of the rod being threaded to receive the nut. And interposed between the nut L and the transverse end wall of the cup-shaped weight H there is provided a coil spring M which normally holds the weight seated against the block D, as shown in Figure 14, and tends to yieldingly oppose its radial movement outward in response to centrifugal force when the propeller revolves.

In order that the propeller blades shall be equally adjusted at all times, they are shown inter-connected by bevel gears P secured to the root end of each propeller blade inside the hub housing A and meshing with bevel pinions Q and R, which are loosely mounted upon the drive shaft C.

Referring to Figures 3, 4 and 5, it should be understood that the arrow X in each instance indicates the direction of rotation of the propeller. In Figure 3 the angle a at which the propeller blade II is shown adjusted, represents the initial position of the blade when at rest. On Figure 4 the angle b indicates the range of adjustment through which the blade may be shifted as the speed increases, the limiting angle shown as approximately 45 degrees corresponding to optimum pitch for full efficiency. Any further movement of the governor weights caused by an increase in the centrifugal force acting upon them, such increase being, in turn, caused by added velocity of rotation of the propeller, will tend to shift the blades II into the angular range indicated at c in Figure 5, which is to be considered as the maximum or "over-revving" setting of the propeller blades at which they offer paddle-wheel resistance, so that the propeller becomes a governor for holding the engine to its maximum intended speed.

In both forms of the invention illustrated herein the pitch of the helical features which interconnect the weights and the hollow shanks of the propeller blades is such that the wind resistance against the blades cannot turn them; in other words, the helical drive between the weights and the blades is irreversible. Thus the blades are held firmly at all positions of adjustment.

I claim:

1. In a variable pitch propeller, a hub and a plurality of blades carried thereby, each blade having a closed hollow shank mounted in the hub for rotation about its own axis, weights guided for movement respectively within said hollow shanks in response to centrifugal force when the propeller revolves, said weights and the inner surfaces of the hollow shanks having inter-engaging helical features, the weights being restrained against rotation whereby the movement of the weights along the shank axes tends to cause rotative adjustment of the propeller blades, a crank plate journaled within the hub, and substantially straight links connecting said crank plate with said weights respectively to insure equal and simultaneous movements of the weights along the respective axes of the blade shanks to synchronize and equalize the adjust-

ment of the blades, and a torsion spring yieldingly connecting the plate to the hub and opposing rotation of the plate in response to the action of centrifugal force on said weights.

5 2. In the combination defined in claim 1, pivotal means connecting one end of each of said links to the crank plate and pivotal means connecting the other end of each link to one of the weights, the link and said connections serving as the means for restraining the weight against rotation about the axis of the propeller blade shank.

10 3. In a variable pitch propeller, a hub and a plurality of blades carried thereby, each blade having a hollow shank mounted in the hub for rotation about its own axis, a weight guided for movement within said hollow shank and along its axis in response to centrifugal force when the propeller revolves, each of said hollow shanks having a gear rigidly secured to its inner end within the hub, pinions inter-meshing with said gears and connecting them for simultaneous and equal rotation, each of the weights and the inner surface of the shank in which it moves having inter-engaging helical features, and means extending from the hub and restraining the weight against rotation whereby its movement along the axis of the shank serves to cause rotative adjustment of the propeller blade, together with separate spring means associated with each of said pinions and yieldingly resisting rotation thereof to prevent back-lash in the gear connections when the blade shanks are rotated.

15 4. In a variable pitch propeller, a shaft, a hub mounted on said shaft and a plurality of blades carried by the hub, each blade having a hollow shank mounted in the hub for rotation about its own axis, a weight guided for movement within said hollow shank and along its axis in response to centrifugal force when the propeller revolves, means whereby such centrifugally induced movement of the weight produces rotative adjustment of the shank of the blade in which it travels, a plate rotatably mounted within the hub connected to the several weights in the blade shanks for rotation in response to their movements within said shanks, and a spring coiled about the axis of the shaft with its ends connected respectively to said plate and said hub to resist rotation of the plate and movement of the weights outwardly within the shanks of the blades and serving to retract the weights inwardly as the speed of revolution of the propeller is reduced.

20 5. In the combination defined in claim 4, means for adjusting the initial tension of said spring at will and accessible from the outside of the hub.

25 6. In a variable pitch propeller, a hub and a plurality of blades carried thereby, each blade having a hollow shank mounted in the hub for rotation about its own axis, and a weight guided for movement within said hollow shank and along its axis in response to centrifugal force when the propeller revolves, said weight and the inner surface of the shank having inter-engaging helical features, a crank plate mounted for rotation within the hub, connecting rods extending from said crank plate to each of the weights in the respective blade shanks and engaged therewith in a manner preventing rotation of said weights within the shanks, said connections to the crank plate insuring equal and simultaneous movements of the weights in response to centrifugal force, and the aforesaid helical features serving to transform such movements into

simultaneous rotative adjustments of the propeller blades, spring means opposing the movement of said crank plate induced by centrifugal force acting upon the weights, gearing inter-connecting the several shanks of the propeller blades for equal and simultaneous rotative adjustment, and means yieldingly opposing the operation of said gearing in the direction induced by centrifugal force acting upon the weights.

7. In a variable pitch propeller comprising a hub, a shaft to which said hub is secured, said hub including a plurality of blade bearings, blades having hollow shanks rotatably mounted in said bearings respectively, a weight guided in each shank for radial movement therein in response to centrifugal force during revolution of the propeller, said weights and the inner surfaces of said

shanks having inter-engaging helical features, a rotatably mounted crank plate coaxial with the shaft, links connecting said crank plate to the weights respectively, said weights being restrained against rotation about the axes of the respective blade shanks whereby their radial movement causes rotation of the shanks and their associated blades, and a spring coiled about the axis of said shaft having one end connected to said crank plate and the other end connected with said hub for yieldingly restricting rotation of the crank plate and corresponding movement of the weights upwardly within the shanks of the blades and serving to retract said weights inwardly as the speed of revolution of the propeller is reduced.
